REUBEN C. BAKER, OF COALINGA, CALIFORNIA.

PLUG FOR WELL-CASINGS.

1,078,895.

Specification of Letters Patent. Patented Nov. 18, 1913.

Application filed November 20, 1911. Serial No. 661,207.

To all whom it may concern:

Be it known that I, REUBEN C. BAKER, a citizen of the United States, residing at Coalinga, in the county of Fresno and State of California, have invented a new and useful Plug for Well-Casings, of which the following is a specification.

This invention relates to plugs for deep well casings, and has for its primary object 10 to provide means for plugging the lower end of the well casing for the lower end of the well to shut out or exclude water and other foreign matter from the lower strata.

It is a further object to provide a suitable 15 plug which may be passed down the well casing after the casing has been inserted into the well and upon the plug reaching the lower end of the casing is adapted to be engaged thereto to close the lower end of the 20 casing.

To the above ends this invention is embodied in the novel construction and combination of parts as hereinafter described and claimed, reference being had to the accompanying drawing, wherein—

Figure 1 is a longitudinal section of the plug, showing the same in position as it is being lowered down the well casing. Fig. 2 is a perspective view of the plug, a fragmental portion of the well casing being shown. Fig. 3 is a view similar to Fig. 1 showing the plug in position at the bottom of the well casing after the well casing has been depressed into the cement at the lower 35 end of the well. Fig. 4 is a section on the line 4—4 of Fig. 1.

Referring in detail to the drawing, the well casing has been designated by the reference character P and the well by the reference character W.

The plug comprises a hollow body embodying a conical top 12 having perforations 13 therein, and an inverted conical bottom 7 having the apex thereof open as designated by the numeral 8, a perforated partition 24 above the bottom having perforations 25 therein, and a tapered intervening throat 6 with the smallest end uppermost, the body having diametrically opposed 45 openings or slots 27 in the sides thereof above the throat and the said throat forming shoulders 26 and 28 at the upper and lower ends thereof respectively. A stem 10 is 50 slidable through the top of the body and through the partition 24 and extends 55 through the opening 8, and on the lower end

thereof is screw threaded an inverted conical valve 9 which is adapted to seat in the opening 8 to close the said opening, and when so seated coöperates with the bottom 7 to present an inverted conical bottom for 60 the plug. A pair of collars 22 and 18 are secured on the stem 10 within the body of the plug, and a coil compression spring is arranged on the stem between the partition 65 24 and the lowermost collar 22 to give an upward tension to the stem. Dogs or pawls 21 are pivoted in the openings 27 in the upper end 5 of the body by pins 20 and have the outer ends thereof eccentric with the 70 pins 20 and toothed, and have inwardly projecting fingers 19 adapted to rest on the uppermost collar 18 when the stem is depressed to retain the dogs in inactive or retracted position. The stem 10 is normally retained 75 in depressed position by a cast iron or other fragile pin 17 passed therethrough in the top of the body, the said pin being of sufficient strength to overcome the tension of the spring 23. The stem 10 is provided with an 80 eye 11 at the upper end thereof for the attachment of a suitable line for the purpose hereinafter described. A split ring or spreader 14 is arranged on the throat 6 and has an upper and outer rabbet 16. A plurality of screws 15 are engaged through the 85 said ring or spreader to engage in the longitudinal slots 18 in the throat 6 to constrain the ring against rotation. The ring 14 is constructed of spring metal and is slidable 90 on the throat 6 between the shoulders 26 and 28.

In use, it being understood that cement, concrete, or other solidifying matter having been previously poured into the bottom of 95 the well as designated by the reference character C and the well casing having been lowered into the well at a point slightly above the cement or concrete therein, the plug is inserted into the upper end of the 100 well casing, the spreader or ring 14 having been compressed within the casing to have an outer tension. The plug is then lowered down the well casing by a suitable means such as are employed for lowering drill bits 105 and the like into deep wells, a line of suitable character being attached to the eye 11 of the stem 10. Upon the plug reaching the lower end of the well casing the ring or annular spreader 14 which is seated against the 110 shoulder 28 upon the plug passing down the well casing, spreads to engage the lower end

of the well casing, the lower end of the well casing fitting into the rabbet 16 of the said ring or spreader. Then by pulling upward on the line which is attached to the stem 10 the cast iron or fragile pin 17 is broken thus releasing the stem whereby the spring 23 forces the stem upward thereby releasing the fingers 19 and seating the valve 9 in the opening 8, the said valve being held open upon the plug being lowered down the casing. The fingers 19 of the dogs 21, being released, swing the dogs outwardly through the openings 27 to bite or engage the walls of the well casing, thereby preventing the plug from dropping out the lower end of the casing, the plug by the upward pull of the line attached to the stem being drawn upward to bring the shoulder 26 against the ring or spreader 14 thereby securely closing the lower end of the casing. In this manner the plug is secured to the lower end of the casing and by depressing the well casing into the cement C in the bottom of the well, the cement is spread thereby to firmly embed the lower end of the well casing in the cement to exclude or shut out water and other foreign matter from the lower strata of the well. It will be noted that upon the plug being lowered down the well casing and the valve 9 being open permits the water and other liquids in the well to pass through the opening 8, apertures 25 and the apertures 13 in the body to permit the plug to pass readily down the casing, and the fingers 19 in engaging the collar 28 retain the dogs or pawls 21 in inactive position. Thus upon the plug being engaged to the lower end of the well casing and the valve 9 being closed and upon the well casing being depressed into the cement a substantial support for the well casing is provided after the concrete or similar matter solidifies and also effectively excludes the ingress of water and other foreign matter from the well as above described.

This invention is particularly adapted for use in oil wells, gas wells and the like, especially those of considerable depth, where it is necessary or desirable to shut out the lower water and other matter from the lower strata of the well, and it will be seen that this plug is both efficient and convenient in its use. This invention also provides means for sealing the lower end of the well casing with a comparatively small amount of cement or concrete, thus preventing the waste which accrues from methods now employed for this purpose.

A plug constructed in accordance with the present invention is comparatively simple and thereby rendered inexpensive to manufacture.

A further feature of the present invention is the fact that the throat 6 in being tapered permits the said throat to spread the ring

14 after the same has been engaged with the lower end of the well and upon the plug being raised by the line attached to the stem 10 to securely bind the said ring against the lower end of the well casing and to also provide a secure joint between the body of the plug and the said ring. 70

It is further understood that this invention is susceptible of alteration in its details within the scope of the appended claims 75 without departing from the spirit of the invention.

What is claimed is:—

1. In a plug for well casings, a body adapted to pass down the well casing, and expandable means carried thereby and adapted to fit slidably and compressibly in the casing so as to expand and engage the lower end of the casing, when the body reaches the lower end of the casing. 80

2. In a plug for well casings, a plug body adapted to pass down a well casing, and a spreader carried thereby and adapted to fit slidably and compressibly in the casing so as to expand and engage the lower end of 90 the casing when the body reaches the lower end of the casing.

3. In a plug for well casings, a body adapted to pass down the well casing, and an expandable split ring carried thereby and adapted to fit slidably and compressibly in the casing so as to expand and engage the lower end of the casing, when the body reaches the lower end of the casing. 95

4. In a plug for well casings, a hollow body adapted to pass down a well casing and provided with means for engaging the casing, a valve for the said body, and means for closing the said valve on the body being engaged to the well casing. 100

5. In a plug for well casings, a hollow body adapted to pass down a well casing and provided with means to engage the casing, a stem slidable through the body and a valve secured on the lower end of the 110 stem adapted to close the passage through the said body.

6. In a plug for well casings, a hollow body adapted to pass down a well casing and provided with means for engaging the 115 casing, a spring pressed stem slidable through the body, a valve secured on the lower end of the said stem adapted to close the passage through the body, and means for normally holding the valve in open position. 120

7. In a plug for well casings, a body adapted to pass down a well casing and provided with means for engaging the casing, a stem slidable through the body, means 125 for normally holding the stem against upward movement, and dogs carried by the body to engage the walls of the casing but normally held in inactive position by the said stem. 130

8. A plug for well casings comprising a hollow body embodying a perforated conical top, an inverted conical bottom having the apex open, a perforated partition above the bottom, and a tapered intervening throat with its smallest end uppermost, the body having openings in its sides above the said throat, a stem slidable through the said top and partition, and extending through the bottom, an inverted conical valve secured on the lower end of the said stem and adapted to seat in the opening in the bottom, a pair of collars on the said stem above the partition, a coiled compression spring on the stem between the partition and the lowermost collar, dogs pivoted in the openings in the upper end of the body and having inwardly projecting fingers adapted to rest on the uppermost collar to retain the dogs in inactive position, a fragile pin for retaining the stem in depressed position, and an expandible ring on the said throat adapted to engage the well casing. 5
9. A plug for well casings, embodying a body adapted to pass down a well casing, means carried thereby for engaging the lower end of the casing, to prevent the upward movement of the body, means carried by the body for engaging the well casing to lock the body against downward movement, and means for normally holding the latter means in inoperative position and for permitting the same to engage the casing when the former has engaged the lower end of the casing. 10
10. In a plug for well casings, a body adapted to pass down a well casing, and an expandible ring carried thereby having an upper rabbet to engage the lower end of the casing. 15
11. In a plug for well casings, a body adapted to pass down a well casing, dogs pivoted to the body and adapted to engage the well casing when free, the dogs having fingers, a stem slidable through the body having means to engage the said fingers so as to normally retain the dogs in inoperative position, and means for normally holding the stem against movement so as to retain the dogs in inoperative position. 20
12. In a plug for well casings, a body adapted to pass down a well casing and having a passage therethrough, well casing 25
- engaging means carried by the body, means carried by the body for closing the passage therethrough, and means for normally retaining the latter means in open position. 30
13. In a plug for well casings, a body adapted to pass down a well casing and having a passage therethrough, well casing engaging means carried by the body, spring actuated means carried by the body for closing the passage therethrough, and means for normally detaining the latter means in open position against the tension thereof. 35
14. In a plug for well casings, a body adapted to pass down a well casing and having a passage therethrough, well casing engaging means carried by the body, a spring pressed valve carried by the body for closing the passage therethrough, and means for normally retaining the valve in open position against the tension thereof. 40
15. In a plug for well casings, a body adapted to pass down a well casing and having a passage therethrough, a stem slidable through the body, a valve on the stem for closing the passage through the body, and a fragile member carried by the body and engaging the stem to normally retain the valve in open position. 45
16. In a plug for well casings, a hollow body including a bottom provided with an opening and having a perforated partition above the bottom, a stem slidable through the partition and passing through the said opening, and a valve on the lower end of the stem to close the said opening. 50
17. In a plug for well casings, a hollow body including a bottom provided with an opening and having a perforated partition above the bottom, a stem slidable through the partition and passing through the said opening, a valve on the lower end of the stem to close the said opening, a spring between the stem and partition tending to close the valve, and means for normally retaining the stem against the tension of the said spring so as to hold the valve open. 55
- In testimony that I claim the foregoing as my own, I have hereto affixed my signature in the presence of two witnesses.
